(57) **CLAIM**

The ornamental design for an exercise device, as shown and described.

DESCRIPTION

FIG. 1 is a perspective view of the exercise device; FIG. 2 is a front elevation view of the exercise device; FIG. 3 is a rear elevation view of the exercise device; FIG. 4 is a left side elevational view of the exercise device; FIG. 5 is a right side elevational view of the exercise device; FIG. 6 is a top plan view of the exercise device; and, FIG. 7 is a bottom plan view of the exercise device. The dashed broken lines shown in the figures represent portions of the article which form no part of the claimed design. The dot-dash broken lines seen in FIG. 3 represent the boundary of the claim and form no part of the claimed design.

1 Claim, 7 Drawing Sheets
